UNITED STATES PATENT OFFICE

121,614

DESIGN FOR A COSMETIC APPLICATOR

Irene B. Kaltenbach, Los Angeles, Calif.

Application February 6, 1940, Serial No. 90,064

Term of patent 7 years

To all whom it may concern:

Be it known that I, Irene B. Kaltenbach, a citizen of the United States of America, residing in Los Angeles, in the county of Los Angeles, State of California, have invented a new, original, and ornamental Design for a Cosmetic Applicator, of which the following is a specification, reference being had to the accompanying drawing, forming a part thereof.

In the drawing:

I claim:

The ornamental design for a cosmetic applicator, as shown.

IRENE B. KALTENBACH.
